ELECTRON DISCHARGE DEVICE

George D. O'Neill, Port Washington, N. Y., assignor to Sylvania Electric Products Inc., a corporation of Massachusetts

Application March 19, 1948, Serial No. 15,933

5 Claims. (Cl. 315—5)

1

This invention relates to electron discharge devices and more particularly to electron discharge devices of the velocity modulation type employing hollow resonators in which a stream of electrons from a cathode is passed through a gap in said resonators and reflected back through the gap by a reflecting electrode. Such devices are commonly known as reflex klystron tubes. It has been observed that in the operation of such devices as generators of high frequency oscillations, a condition is frequently encountered wherein the reflector voltage for oscillation may change during operation of the oscillation and after operating conditions have apparently been stabilized. The required readjustment of the potential of the reflector to maintain oscillation may be of such magnitude that oscillation will not again commence at the new value of reflector voltage if the tube is turned off and allowed to cool for a period which may vary from seconds to hours. This effect may be called "mode jumping." The tube may operate in one or more distinct and mutually exclusive modes in which the number of the mode is designated N such that $N=fT$ where f is the resonant frequency and T is the time an electron spends in the drift space—the space between resonator grid and reflector. Also, $N=(n-\frac{1}{4})$ where n is an integer greater than zero. The time T depends upon the field in the drift space. If all other charged bodies are far removed, T depends upon the reflector voltage. Specifically,

$$T = \frac{4x}{V} \frac{e_b}{e_b - e_r}$$

where x is the grid-reflector spacing, V is the electron velocity at the grid, e_b is the grid voltage and e_r is the reflector voltage. Often the change in potential of the bulb is such that the tube does not stop oscillating, but shifts or jumps from one mode to another. Now, since the direct potential of the reflecting electrode is different from that of the grid electrodes or apertures associated with the hollow resonator, insulation must be provided in the tube between these elements. Such insulating means may constitute a part of the envelope of the tube. It appears that the "mode jumping" referred to above may be caused by a change in surface potential of the insulating walls of the tube between the reflector electrode and the resonator electrodes. This change in potential affects the field distribution in the retarding region between the resonator and the reflector electrode and therefore requires a compensating change in the reflector potential. If the tube is then turned off, the surface charge

2

may leak off. When the tube is again turned on the potential on the reflector electrode must be returned to its original value.

An object, therefore, of the present invention is to provide a means for stabilizing the retarding field between the grid associated with the resonator and the reflector.

Another object of the present invention is the provision of means for stabilizing the mode of operation of a reflex electron beam oscillator.

Still another object of the present invention is the improvement of the stability of operation of a reflex klystron.

Experiments which have been made seem to indicate that the change in potential of the envelope between the reflector electrode and the resonator electrodes, is a result of its being struck by charged particles. Since the change required in the reflector voltage after oscillation starts is usually in the negative direction, it appears that the glass surface has become positively charged due, presumably, to the emission of secondary electrons caused by its having been bombarded by primary electrons originating at the cathode of the tube and passing through the resonator grids but are not returned to the grid by the reflector electrode. In the absence of special means to prevent the bombardment of the envelope by the primary electrons, it is impossible to maintain steady oscillation or to predict the reflector voltage required for oscillation in a given mode, since the surface charge on the glass is not constant. When the present invention is employed in the operation of the electron discharge tube, it is found that operation is constant and the voltage conditions for the various modes of operation are constant. This is substantially true with regard to any individual tube of the same design, or to a given tube substantially regardless of time or temperature variations.

In accordance with an aspect of the present invention, the building up of a charge on the glass envelope may be prevented by providing a maze between the reflector electrode and resonator electrodes which prevents the electrons from the cathode from reaching the inner surface of the envelope. Alternatively the inner surface of the glass envelope of the tube may be so treated as to prevent either a bound charge on the glass surface or secondary emission from the surface of the glass.

The present invention will be more fully understood by reference to the following detailed description which is accompanied by a drawing in which

Fig. 1 illustrates in partial longitudinal cross-section a tube embodying the principles of the present invention, while

Fig. 2 is a longitudinal cross-section of a portion of a modified form of the invention, while

Fig. 3 is still a further modification shown in longitudinal cross-section.

As shown in the drawing, reference numeral 10 indicates the evacuated glass envelope of an electron discharge device having at one end a 10 cathode structure 12. The cathode structure 12 incorporates a heated electron emissive surface and focusing means for producing a beam of electrons. Said beam is projected through grid 13 in apertured electrode 14 and through grid 15 in apertured electrode 16. Electrodes 14 and 16 are in the form of conductive metal discs passing through the wall of the glass envelope 10 of the tube. Preferably they terminate in cylindrical rims 18 and 20 adapted to make good contact 20 with the walls of an exterior resonating chamber. The resonating chamber is not shown since it may be of various forms and of varying dimensions, depending upon the desired frequency of operation of the system. The stream of electrons from cathode 12, after passing through grids 13 and 15, is reflected back through the resonator gap between grids 13 and 15 by the suitable negative potential in reflector electrode 22. The energizing potentials on the electrodes 25 of the tube are so related to the dimensions of the tube and the associated resonating chamber as to cause the reflected electrons to pass back through the gap between electrodes 13 and 15 in bunches, thus exciting the associated resonant 30 cavity into oscillation.

In the tube, as so far described, and without the provision of some special means of preventing such action, electrons may so far fail to be influenced by the reflector electrode 22 as to 40 pass between the edges of the reflector electrode 22 and the electrode 16 and strike the glass wall of envelope 10. They may strike the envelope with sufficient velocity to cause the emission of 45 secondary electrons. The emission of such electrons from the glass results in a bound positive charge thereon which affects the electric field distribution between the resonator and reflector electrode to such an extent that the reflector voltage must be adjusted to maintain the desired mode of operation. It should be noted 50 that the action may start as the result of a very few electrons striking the wall—maybe one in a billion. When a single electron strikes the 55 wall and ejects two or more secondaries, it leaves a small, positively-charged spot which attracts more electrons. As the spot begins to grow it may pull more electrons to it so that, after a while, it may grow very rapidly. For 60 example, it may take five minutes to reach a critical size, then pull so many electrons to it that in a matter of a second or less the whole bulb jumps up to a condition of full positive charge all over. Such charge can only slowly be dissipated, due 65 to the high resistance of the glass surface. In the modification shown in Fig. 1, in order to prevent such action, I have provided a maze including a cup-shaped electrode 24, electrically connected to electrode 16 and having an inturned edge 26. Over cup-shaped electrode 24 is a 70 second cup-shaped electrode 28 electrically connected to the reflector electrode 22 and having down-turned edges 30 overlapping the upper edge of cup-shaped electrode 24. Thus, a tortuous path is provided between the space between

electrode 22 and screen 15, through which no electrons may escape to strike the surface of wall 10. Thus the potential distribution between electrode 22 and electrode 16 is maintained constant, and a constant mode of operation is attained for the electron discharge tube.

An alternative form of the invention is shown in Fig. 2 wherein the glass envelope 10 is provided with a conductive coating on its inner surface extending from the ring electrode 16 upwardly to within a short distance of the seal through which the lead-in wire for reflector electrode 22 passes. The conductive coating should be of a material which has an inherently low coefficient of secondary emission, such as a thin coating of graphite applied as a suspension in alcohol and sprayed onto the glass. The coating preferably extends from the disc electrode 16 upwardly to at least a point above the region likely to be bombarded by primary electrons.

In the further modification shown in Fig. 3, instead of utilizing a glass envelope in the region between the ring electrode 16 and the point where the support and lead-in electrode for electrode 22 passes, a metal shell 35 electrically connected to ring electrode 16 is provided. The necessary insulation between the lead-in for electrode 22 and the metal shell 35 is provided by a glass bead seal 38. It will be apparent that in the modifications shown in Figs. 2 and 3, the wall of the electron tube between ring electrode 16 and up beyond a point where electrons from the cathode may strike the wall, is maintained at a constant potential equal to that of the ring electrode. The conductive coating or conductive wall, as the case may be, positively prevents the formation of a bound charge on the wall of the envelope either due to secondary emission or due to the collection of electrons from the cathode structure 12. Thus, a constant mode of operation of the tube is assured.

While I have described particular embodiments of the present invention for purposes of illustration, it will be understood that various modifications and adaptations thereof may be made within the spirit of the invention, for example, other forms of maze construction for preventing electrons emitted from the cathode from reaching the glass envelope may be used.

What is claimed is:

1. A high-frequency tube including an evacuated envelope containing an electrode for providing a stream of electrons and a reflector electrode toward which said stream is to be directed, a pair of apertured disc electrodes interposed in the path of said stream, said envelope being coated on its interior with a conductive material from the second of said disc electrodes to a point adjacent said reflector electrode.
2. A high-frequency tube including an evacuated envelope containing an electrode for providing a stream of electrons and a reflector electrode toward which said stream is to be directed, a pair of apertured disc electrodes interposed in the path of said stream, said envelope being coated on its interior with a conductive material from the second of said disc electrodes to a point adjacent said reflector electrode, said coating being connected to said second disc electrode.
3. A high-frequency tube including an evacuated envelope containing an electrode for providing a stream of electrons and a reflector electrode toward which said stream is directed, a pair of apertured disc electrodes interposed in the path of said stream, said envelope being coated on its

interior with a thin layer of graphite from the second of said disc electrodes to a point adjacent said reflector electrode.

4. A high-frequency tube including an evacuated envelope containing an electrode for providing a stream of electrons and a reflector electrode toward which said stream is directed, a pair of apertured disc electrodes interposed in the path of said stream, said envelope being coated on its interior with a thin layer of graphite from the second of said disc electrodes to a point adjacent said reflector electrode, said coating being connected to said second disc electrode.

5. A high-frequency tube including an evacuated envelope containing an electrode for providing a stream of electrons and a reflector electrode toward which said stream is to be directed, a pair of apertured disc electrodes interposed in the path of said stream, said envelope being

coated on its interior with a material inhibiting the emission of secondary electrons from the second of said disc electrodes to a point adjacent said reflector electrode, said coating being connected to said second disc electrode.
